UNITED STATES PATENT OFFICE.

CHARLES J. WAUGH AND FRITZ HARENDE, OF CAMDEN, NEW JERSEY.

CYLINDER-LOCK.

No. 900,627.

Specification of Letters Patent.

Patented Oct. 6, 1908.

Application filed December 10, 1907. Serial No. 405,914.

To all whom it may concern:

Be it known that we, CHARLES J. WAUGH and FRITZ HARENDE, citizens of the United States, residing at Camden, in the county of 5 Camden and State of New Jersey, have invented certain new and useful Improvements in Cylinder-Locks, of which the following is a specification.

Our invention relates to cylinder locks, 10 and has for its object the production of a lock belonging to the class having series of pins abutting end to end and adapted for arrangement by means of a key in such manner that the cylinder may be turned and the 15 parts unlocked, our invention consisting in the special construction and arrangement of the various essential parts.

We accomplish the stated object by fashioning and associating the parts as illustrated in the accompanying drawings, of which

Figure 1 represents a vertical section lengthwise through the lock. Fig. 2 is a cross-section of our invention applied to a 25 door. A portion of the door is also shown sectionally. Fig. 3 is a face view of the surface or side of the lock which is to be placed against a door.

Like letters of reference are employed to 30 designate the same parts throughout.

Considering the drawings, the casing of the lock is marked A, and the bolt B. The bolt has a special form. It extends from the front of the lock upwardly as shown and is 35 provided with a surface or side b resting in movable contact with the inside of the top of the casing. The bolt extends rearwardly and then downwardly substantially at right angles with the surface b, and the foot of 40 the bolt has a surface b' resting movably against the inside of the lower portion of the casing. The two surfaces or sides of the bolt mentioned are parallel one to the other, and as the bolt moves it is guided by those 45 surfaces against the parallel surfaces of the casing. It will be here noted that the particular shape of the bolt leaves the middle portion of the casing unoccupied for the reception of other parts to be described.

50 The bolt B is yielding held in locking position, that is to say, with its head projecting beyond the casing, by the spring C, one end of which is attached to the post D projecting from the bolt laterally, and the remaining end of the spring is secured to the 55 post E projecting from the inside of the cas-

ing. Thus, when the bolt is moved to the right, it encounters the force of the spring C which returns it into the position shown in the drawings when the unlocking effort is withdrawn. The bolt is directly operated by the plate F, one end of which is secured upon the inner end of the cylinder G. One of the screws by which the plate F is attached to the cylinder is shown in Fig. 2. 60 As the cylinder turns the free end of the plate is brought edgewise against the bolt, moving it to the right as will readily be understood from the drawings. The cylinder G occupies a corresponding orifice in the 65 housing H, and upper and lower extensions J and K are formed integrally with the middle portion H. Those extensions are diametrically opposite each other and each is provided with a row of pin holes j and k, in 70 which are arranged the pins L and springs M, the springs being beneath the pin in each hole and tending to force the pin beyond the mouth of the hole. The cylinder G is provided with a number of corresponding holes 75 in which are the relatively shorter pins N, without springs beneath them.

Now considering Fig. 2, there will be noted the escutcheon O as an entrance for the key Q. The key passes entirely through 80 the door P, and the passage p therefor, it will be seen, is relatively very small, being in fact sufficient only for the introduction and rotation of the key. Here it may be stated that the mechanism of the lock is 85 wholly contained in the casing, no part of the cylinder or other element being inserted into the door.

The cylinder housing H, and its extensions J and K are usually integral parts of 90 the plate R, shown in Fig. 3, and this plate lies against the door when our invention is in position.

The key Q is a split key, and has two sinuate edges. When the key is inserted as illustrated in Fig. 2, the abutting ends of the pins L and N coincide with the surface of the cylinder which may be turned by the key. A middle portion g of the cylinder enters the split or recess in the end of the 105 key.

It is thought to be now clearly made out that by reason of the special form and arrangement of the bolt B, room is made with in the casing for the two extensions of the 110 cylinder housing H, and thus the special form and arrangement of that housing be-

comes practicable. Further, as a result of the construction and disposition of parts as described, all the lock mechanism is included within the casing and the whole rendered as compact as it is believed can be done.

Having now described the construction and arrangement constituting our invention, what we claim is—

1. In a cylinder lock, the combination with a casing, the opposite sides of the casing having parallel interior surfaces, a bolt having a surface in contact with one of said parallel surfaces of the casing, the said bolt having a rear portion extending across the interior of the casing and the end of said portion of the bolt being arranged in contact with the other parallel surface of the casing, a revoluble cylinder and a cylinder housing having corresponding spring pins, and a device actuated by the cylinder and arranged to act against the said rear portion of the bolt to move the bolt, substantially as described.

2. In a cylinder lock, the combination with a casing, the opposite sides of the casing having parallel interior surfaces, a cylinder

and a cylinder housing provided with corresponding spring pins whereby the cylinder may be locked and unlocked, the said housing being arranged transversely within the casing, and a bolt having a horizontal portion passing above the said housing and provided with a surface arranged movably against one of the said parallel interior surfaces of the casing, the said bolt having a vertical rear portion integral at its upper end with the said horizontal portion, the lower end of the said vertical rear portion of the bolt being arranged movably against the remaining parallel interior surface of the casing, and a plate attached to the cylinder and arranged to act against the said rear portion of the bolt to move the bolt, substantially as described.

In testimony whereof we affix our signatures in presence of two witnesses.

CHARLES J. WAUGH.
FRITZ HARENDR.
